UNITED STATES PATENT OFFICE.

OLIVER I. TAWNEY, OF TURKEY, ARIZONA.

TRAY-LIFTING DEVICE FOR SHOW-CASES.

1,098,994.

Specification of Letters Patent.

Patented June 2, 1914.

Application filed December 2, 1913. Serial No. 804,290.

To all whom it may concern:

Be it known that I, OLIVER I. TAWNEY, a citizen of the United States, residing at Turkey, in the county of Yavapai and State of 5 Arizona, have invented new and useful Improvements in Tray-Lifting Devices for Show-Cases, of which the following is a specification.

An object of the invention is to provide 10 a device for use in connection with trays and show cases and which is adapted to support boxes of goods whereby the trays carrying the goods can be raised into position to permit the customer to select the goods he 15 desires from the box.

The invention embodies, among other features, the provision of a device particularly adapted for use in connection with show cases containing boxes of cigars and the 20 like, and in which it is desired to have the customer select his own purchase from the box, thus making it necessary to raise the box a distance within the show case to permit of readily removing the article from the 25 box.

In my invention I aim to provide a device whereby the salesman can readily lift the tray and box carried thereby into a position whereby the customer can easily select 30 his purchase from the box, after which the tray and box are returned to their proper position within the show case.

In the further disclosure of the invention reference is to be had to the accompanying 35 drawings, constituting a part of this specification, in which similar characters of reference denote corresponding parts in all the views, and in which:

Figure 1 is a fragmentary perspective 40 view of my device, the full lines indicating the normal position of the tray and the dotted lines indicating one of the trays in raised position; Fig. 2 is a vertical transverse sectional view taken through the show 45 case and showing the manner of operating the trays; and Fig. 3 is a fragmentary vertical sectional view showing the arrangement of the spring for aiding in returning the trays to normal position.

Referring more particularly to the views, I disclose a show case 10 having the usual horizontal partition 11 on which are arranged a series of trays 12. A stem 13 projects from the under side of each tray and through an opening 14 formed in the partition 11 and the lower end of the stem has

pivotal connection with a rod 15 lying beneath the partition and extending upwardly and rearwardly toward the back of the show case 10, the said rod between its ends having 60 pivotal connection with a depending supporting member 16 secured to the under side of the partition. The free end of the rod 15 has pivotal connection with an actuating member 17 extending vertically at the rear 65 of the show case and operating in a groove 18 formed in a bar 19 supported horizontally on the rear of the show case. The upper end of the actuating member 17 terminates in a suitable knob 20 and the actuating member is provided with an integral lug 21 preferably formed immediately beneath the knob 20.

As shown in Fig. 1 when the trays 12 are in normal position they repose upon the partition 11 and when it is desired to move one of the trays into position so that a box 22 carrying suitable goods can be raised to a position relatively to the show case to permit of the ready removal of the goods from 80 the box, the usual cover 23 of the show case is first slid into open position as shown and a downward pressure is then exerted on the knob 20, thus imparting a downward movement to the inner end of the rod 15 and 85 consequently moving the stem 13 upwardly, thus carrying the tray 12, having the box 22 thereon, upwardly in the show case into a position which will permit of the purchaser readily removing the goods he desires from 90 the box. In order to secure the tray in its uppermost position the actuating member 17, when being moved downwardly, is pushed slightly inwardly to permit the lug 21 to pass through the groove 18 and then by 95 pulling slightly inwardly on the upper end of the actuating member it will be apparent that when pressure is released on the actuating member the lug 21 will abut against the under side of the bar 19, thus holding 100 the tray in raised position. When the purchaser has removed the goods he desires from the box, the salesman first swings the actuating member slightly forward to disengage the lug 21 from the under side of 105 the bar 19 and then the actuating member can be readily raised upwardly to normal position due to the weight of the goods upon the tray and which will result in the tray being returned to normal position within the 110 show case so that the tray will lie upon the partition 11 as shown in full lines in Fig. 1.

In order to facilitate the operation of the tray I preferably provide a spring 24 coiled around a pin 25 pivotally connecting the rod 15 with the actuating member 17, with 5 one end of the spring abutting against the rod and the other end abutting against the actuating member.

From the foregoing description it will be apparent that with a device of the character 10 described a tray containing goods and normally lying wholly within the show case can be readily raised into position to permit of the purchaser easily helping himself to the goods he desires, after which the tray can 15 be conveniently returned to normal position within the show case and the cover of the show case closed to protect the articles in the boxes within the show case.

Having thus described my invention, I 20 claim:

1. In combination with a show case having a partition, a tray normally reposing upon the partition, a stem carried by the tray and projecting through an aperture in 25 the partition, a rod having pivotal connection with the stem, an actuating member having pivotal connection with the rod, a supporting member depending from the partition and having the rod mounted to swing thereon between its ends, a bar supported 30 on the show case and having a groove therein, and a lug carried by the actuating member and adapted to engage the under side

of the bar when the actuating member is operated to raise the tray in the show case, 35 so that the said lug engaging the said bar will hold the tray in raised position.

2. In combination with a show case having a partition, a tray normally reposing upon the partition, a stem carried by the tray and projecting through an aperture in the partition, a rod having pivotal connection with the stem, an actuating member having pivotal connection with the rod, a supporting member depending from the partition and having the rod mounted to swing thereon between its ends, a bar supported on the show case and having a groove therein, a lug carried by the actuating member and adapted to engage the under side of the bar 45 when the actuating member is operated to raise the tray in the show case, so that the said lug engaging the said bar will hold the tray in raised position, and a spring having engagement with the said actuating 50 member and the said rod for returning the tray to normal position within the show case when the said lug is disengaged from the said tray.

In testimony whereof I affix my signature 60 in presence of two witnesses.

OLIVER I. TAWNEY.
